FUEL INJECTOR FOR DIESEL ENGINES

Joseph B. Ziegler, South Bend, Ind.

Application October 22, 1948, Serial No. 56,035

10 Claims. (Cl. 123—33)

1

This invention relates to improvements in fuel injectors for Diesel engines.

The primary objects of the invention are to provide an injector by means of which fuel may be injected to a Diesel engine during a large portion of each cycle of operation of the engine, wherein the pressure of the fuel required for feeding the same is held at a low value compared to the pressure at which fuel is conventionally injected into a Diesel engine, wherein the construction avoids the necessity of injecting fuel into an engine cylinder against high cylinder pressure therein, wherein the necessity for an expensive fuel metering pump is avoided and a simple low pressure fuel pump may be employed, and wherein novel cooling action of the injector is provided.

Other objects will be apparent from the following specification.

In the drawing:

Fig. 1 is an axial sectional view of one embodiment of the injector.

Fig. 2 is an enlarged fragmentary view illustrating one position of the injector.

Fig. 3 is a view similar to Fig. 2 illustrating a second position of the injector.

Fig. 4 is an axial sectional view of a modified embodiment of the invention.

Fig. 5 is a sectional view of the injector taken on line 5—5 of Fig. 4.

Referring to the drawing, and particularly to Figs. 1 to 3 thereof which illustrate one embodiment of the invention, the numeral 10 designates the head of a cylinder of an internal combustion engine within which a piston (not shown) reciprocates in a manner well understood in the art. The head 10 has a bore therein adapted to receive the injector, which bore preferably has a tapered mouth parts 12, an oppositely tapered socket portion 14, and an internally screw-threaded outer portion 16.

Within the bore of the cylinder head as described is mounted an injector including a nozzle having a cylindrical body portion 18 screw-threaded in the portion 16 of the bore, and a tapered portion 20 having a snug pressed fit within the tapered portion 14 of the bore. The outer end of the nozzle projects from the outer surface of the cylinder head 10 and has an enlarged flange 22 of suitable configuration to facilitate its insertion into the bore by the use of wrenches or other tools.

An elongated valve stem 24 extends centrally or axially through the nozzle, being preferably provided at its inner end with a reduced di-

2

ameter portion 26 from which projects inwardly a portion 28 having a snug sealing and sliding fit within the bore of the tip portion of the nozzle. An enlarged flange 30 is formed at the inner end of the valve stem and is adapted to bear against the end surface of the nozzle tip. The valve stem 24 is slidable within an elongated tubular guide 32 having a circumferential flange 34 formed intermediate its ends. A ring 36 bears upon and is supported by a shoulder 38 formed in the interior of the nozzle, and the circumferential flange 34 bears against the said ring. A sleeve 40 is screw-threaded into the cylindrical portion 18 of the nozzle and is provided with an external flange 42 at its outer end adapted for application of a tool, such as a wrench, thereto. The sleeve 40 has an inwardly projecting circumferential flange 44 adapted to bear upon the flange 34 of the guide 32. A coil spring 46 encircles the upper ends of the valve stem 24 and the valve guide 32, with its lower end portion fitting within the retainer 40 and bearing against the internal shoulder or flange 44 thereof. The upper end of the valve stem 24 mounts a head 48 and a sleeve guide member 50 provided with a circumferential flange 52 intermediate its ends. The upper end of the coil spring 46 fits around the lower portion of the sleeve guide 50 and bears against the flange 52.

30 The cylinder head has a fuel intake passage 54 formed therein and a sleeve 56 is screw-threaded in said passage to a position bearing against a shoulder between said portion 54 and a reduced portion 58 of the passage. A spherical valve element 60 is mounted in and free to shift lengthwise in the passage portion 58 which is provided with a reduced terminal portion 62. The shoulder between the passage portions 58 and 62 is preferably ridged at 64 to form a stop for the sphere 60 which prevents its closing the passage portion 62. The passage portion 62 communicates with the tapered portion 14 of the bore adjacent the lower or inner portion thereof, and a circumferential groove 66 is formed in the tapered portion 20 of the nozzle and registers with the passage portion 62. One or more small bores 68 are formed in the tip portion of the nozzle, communicating at one end with the groove 66 and at its opposite end with the outer or tip transverse surface of the nozzle. A second restricted bore or group of bores 70 is formed in the nozzle, communicating at one end with the groove 66 and at its opposite end with the inner surface of the tapered portion 20 of the nozzle spaced inwardly 55 from the portion engaged by the valve part 28.

The engine will be provided with a suitable valve operating cam shaft in the manner well understood in the art, and the valve head 48 will be positioned to be engaged by a cam upon said shaft for the purpose of longitudinally shifting said valve stem 24 against the action of the spring 46. The movement of the valve stem for valve operating purposes will occur in properly timed relation, as is understood in the art, and two of the open positions of the valve are illustrated in Figs. 2 and 3. The fuel passage 54 will be connected with a source of fuel, as by means of a low pressure fuel pump. The engine will also be provided with means for intake and exhaust of air, as is also well understood in the art.

The parts are illustrated in Fig. 1 in the position occupied during the compression stroke of the engine. Note that the valve head 28, 30 seals the end of the nozzle but that fuel may be supplied through the passage 54, the bore of the sleeve 56, the passage 58 around the spherical valve 60, the passage 62, the groove 68 and the passage 70. The closed position of the valve head 28, 30 seals the interior of the nozzle against the pressure existing within the engine cylinder, and, consequently, the flow of fuel into the interior of the nozzle through the passage mentioned above may occur at a pressure much lower than normal injection pressures in Diesel engines.

The cam for actuating the valve will be so arranged that until the compression within the cylinder has reached a predetermined value incident to the compression stroke of the piston, for example, a value in the neighborhood of 100 pounds per square inch, the valve will be actuated to a slightly or partly open position, as illustrated in Fig. 2. The cracking of the valve in the Fig. 2 position permits air under pressure to pass from the cylinder through the bore 68, the groove 66 and the bore 70 into the interior cavity of the nozzle. This air mixes with the fuel in the groove 68 and in the interior of the nozzle. At the same time the pressure of the air so discharged from the cylinder into the groove 66 acts against the valve element 60 to shift the same in the portion 58 of the fuel passage to a position bearing against the inner end of the sleeve 56 and sealing the bore of said sleeve when air pressure exceeds fuel pressure. The valve 28, 30 is then closed, i. e. when pressure reaches approximately 100 pounds, and the compression stroke of the piston of the engine continues until a predetermined time shortly before the connecting rod (not shown) which is connected with said piston reaches dead center. The engine cam engaging the head 48 will be of such contour that at this time the valve is reopened to the position shown in Fig. 3. The time of reopening of the valve will be correlated with the stroke of the piston so that, when the valve is open to the Fig. 3 position, the air within the cylinder will have been compressed to an extent generating heat sufficient to ignite the charge contained within the injector nozzle and pre-combustion will occur within the nozzle. The pre-ignition will occur by the time the piston has reached dead center, and the pre-ignition will force air-fuel mixture from the injector body into the cylinder around the reduced portion 26 of the valve stem, thereby causing ignition within the cylinder itself to generate the power required for the power stroke of the engine. As soon as the power stroke and the subsequent exhaust of the products of combustion from the cylinder has been

completed, the cam will permit the valve to again close, whereupon the supply of fuel at low pressure can again commence.

It will be apparent that this device permits the feeding of fuel through a large part of each cycle of the engine. Also, the feeding of the fuel can occur against substantial atmospheric pressure; hence the fuel can be supplied at a much lower pressure than is conventionally utilized in fuel injectors for Diesel engines and at the same time assure the feeding of an adequate amount of fuel for proper engine operation.

A modified embodiment of the invention is illustrated in Figs. 4 and 5, wherein the head 10 of the engine cylinder has a substantially cylindrical bore 80 terminating at its inner end in a conical enlarged portion 82. A cylindrical sleeve 84 is screw-threaded or otherwise secured within the bore and preferably terminates at a point adjacent to the junction of portions 80, 82 of the bore. The cylindrical member 84 has an enlarged externally projecting flange 86 at its upper end positioned outwardly of the head 10 and an annular sealing gasket 88 is interposed between said head 10 and flange 86. The lower portion of the sleeve is preferably provided with a tapered surface 90 forming a valve seat. A circumferential groove 92 is formed in the external surface of the sleeve 84, and one or more passages 94 open at the tapered surface 90 communicating with said groove. One or more additional passages 96 communicate with the groove 92 and are open at the inner face of the sleeve 84 in spaced relation above the tapered surface 90 of said sleeve.

The head 10 is provided with a fuel passage

of substantially the same construction hereinabove defined, including a reduced terminal portion 98, an enlarged elongated portion 100 receiving a ball valve 102, and a sleeve 104.

A valve stem 106 is positioned coaxially of the sleeve 84 and extends through a central aperture in a closure plate 108 mounted upon and spanning the upper end of the sleeve 84. A coil spring 110 encircles the valve stem 106 and bears at its opposite end upon a head (not shown) mounted upon the upper or free end of the valve stem. The valve stem mounts a valve plunger 112 whose upper portion is cylindrical and has a snug sliding fit within the sleeve 84. One or more circumferential grooves are formed in the inner or upper part of the valve 112 and receive sealing rings 114, such as conventional piston rings. The intermediate portion 116 of the valve plunger is formed of reduced dimension. The inner or lower portion of the valve plunger includes a cylindrical portion 118 adapted to have a snug sliding fit in the end of the sleeve 84 and an enlarged conical portion 120 adapted to seat against the conical valve seat 90. The parts are so proportioned and arranged that the cylindrical portion 118 terminates outwardly of or below the mouth of the aperture or apertures 96 when the conical portion 120 is fully seated upon the seat 90.

The head 10 is provided with a valve insert 122 seated in a tapered opening communicating with the bore 80 intermediate the end thereof. The valve seat has a tapered or frusto conical outer surface which fits snugly within the tapered receiving bore therefor in the head 10 and may be provided with an enlarged flange 124 at its outer end adapted to receive bolts or other securing means 126 for securing said insert to the block. The sleeve 84 is provided with a conical aperture registering with the insert receiving bore

of the head 18, and the insert extends through this opening. The valve insert has a bore 128 extending for a part only of the length thereof and is provided with a valve seat 120 at its inner end. A lateral aperture 132 is formed in the insert in communication with the bore 128. The outer end of the insert has a reduced bore portion 134 which slidably receives and guides a valve stem 136 mounting a valve head 138 adapted to bear against the valve seat 120. An air intake passage 140 is formed in the head, and the lateral opening 132 of the insert communicates therewith. A coil spring 142 encircles the outer end of the valve stem 136 and bears against a head (not shown) for the purpose of normally urging the valve 138 to seated position. The head of the valve 138 is preferably of a diameter slightly less than the diameter of the insert at its smallest or inner end. The insert is so positioned and of such size that it communicates with the interior of the cylinder or sleeve 84 intermediate the portions 112 and 118 of the valve and is spaced therefrom a distance greater than the full travel of the valve plunger between its fully open and fully closed positions.

This device possesses the same advantages and can be used in the same manner as described above. Observe that when the valve 120 is seated against the valve seat 90, the supply of fuel under low pressure through the fuel intake ports 93 and 100 past the ball valve 102 is permitted. The valve may be opened partially, as illustrated in Fig. 4, to permit the flow of compressed air from the cylinder to the port 94, the groove 92 and the port 96, to the space within the sleeve 84 between the head portions 112 and 118 of the valve plunger. Any pressure existing within this sleeve between the two valve plungers acts equally in opposite directions so that the spring 110 of the valve is not subjected to any load incident to the mixing of fuel and air in the chamber around the reduced portion 116 of the plunger. That pressure will tend to act against the valve head 138 to urge it to seated position. While the valve is in this cracked position, the portion 118 of the valve maintains its sealing fit within the inner or lower end of the sleeve 84 to prevent direct communication between the interior of the sleeve and the engine cylinder. Closing of the valve permits continued supply of fuel if the pressure within the chamber around the stem portion 116 does not exceed the pressure at which the fuel is supplied. Full opening of the valve to a position at which the plunger part 118 is clear of the sleeve 84 may be obtained by a proper throw or movement of the valve stem 116 at the commencement of and during the power stroke and during the air intake stroke or portion thereof.

The primary advantage of this device, over and above that shown in Fig. 1, is that the same provides a large chamber for receiving air and also permits a fast flow of air from that chamber into the engine cylinder upon ignition at the beginning of the ignition or working stroke. A further advantage is the fact that the forces acting upon the valve by reason of the equal size of the valve portions 112, 118 are equal. Cooling of the injector is also facilitated by reason of the flow of intake air into the cylinder through said injector. It will be understood that suitable means (not shown), such as timing cams, will serve to operate the valve stem 136 in proper timed sequence relative to the sequence of operations of the valve stem 106.

It will be understood that any suitable means (not shown) will be provided for controlling the flow of fuel to the cylinder of the engine in both embodiments of the invention illustrated. This means may take any form found suitable and will serve the purpose commonly served by the accelerator or fuel control element for the control of speed of a conventional internal combustion engine, as is well understood in the art.

10 While the preferred embodiments of the invention have been illustrated and described herein, it will be understood that changes may be made in the construction within the scope of the appended claims without departing from the spirit of the invention.

I claim:

1. In a Diesel engine, an engine cylinder including a wall having an opening therethrough and a fuel passage communicating with said opening adjacent to its inner end, a check valve in said fuel passage, a nozzle mounted in said opening, a valve including a head in said cylinder adapted to seal the inner end of said nozzle and a valve stem projecting through and outwardly from said nozzle, and means sealing the outer end of said nozzle to define an auxiliary combustion chamber therein, said nozzle having a groove in its outer surface communicating with said fuel passage, and a pair of passages communicating with said groove, one of said passages communicating with said auxiliary combustion chamber and the other opening at the end surface of said nozzle and adapted to communicate with the interior of said cylinder, said valve normally seating against the end surface of said nozzle to seal said last named passage.

2. In a Diesel engine, an engine cylinder including a wall having an opening therethrough and a fuel passage communicating with said opening, a check valve in said passage, a hollow member seated in said opening to define an auxiliary combustion chamber and having an aperture and a valve seat surrounding said aperture, and a valve normally engaging said seat to seal said aperture and including a stem having a snug sliding fit in said aperture, said chamber having a recess in its outer surface communicating with said fuel passage, and a pair of passages branching from said recess and respectively open at said valve seat to communicate with said cylinder and at an inner surface of said member spaced from said aperture to communicate with said auxiliary chamber.

3. In a Diesel engine, an engine cylinder including a wall having an opening therethrough and a fuel passage communicating with said opening, a check valve in said passage, a hollow member fitting in said opening to define an auxiliary combustion chamber and having an aperture surrounded by a valve seat, a valve having a head normally engaging said seat and a portion having a snug fit in said aperture, said hollow member having a pair of passages each communicating at one end with said fuel passage, one of said last named passages opening at said valve seat for communication with said cylinder and the other opening into said auxiliary chamber spaced from said aperture.

4. The construction defined in claim 3, where-in said valve includes a valve stem having a portion adjacent to said valve head of a cross-sectional size smaller than the size of said aperture.

5. The construction defined in claim 3, where-in the inner portions of said wall opening and hollow chamber defining member are of mating

tapered contour and said fuel passage communicates with the tapered portion of said wall opening and said last named passages are formed in the tip portion of the tapered end of said hollow member.

6. The construction defined in claim 3, wherein in said valve includes a stem having a portion adjacent to said head of smaller cross-sectional size than said aperture and a portion projecting from said member, a valve guide carried by said member and receiving said stem, said stem projecting through and externally of said auxiliary chamber, a coil spring encircling the outer portion of said stem and bearing against said member, and a spring abutment mounted on the outer end of said stem.

7. In a Diesel engine, an engine cylinder including a wall having an opening therethrough and a pair of spaced passages communicating with said opening for supplying fuel and air, respectively, a check valve in said fuel passage, a hollow member seated in said opening to define an auxiliary combustion chamber, said member having a valve seat open at said cylinder and a second valve seat communicating with said air passage, a pair of valves each normally engaging a valve seat, said hollow member having a pair of ports each communicating with said fuel passage, one port opening at the valve seat communicating with said cylinder and the other port communicating with said auxiliary combustion chamber.

8. In a Diesel engine, an engine cylinder including a wall having an opening therein and spaced passages for fuel and air communicating with said opening, a cylindrical sleeve fitting in

said opening to define an auxiliary combustion chamber and having a valve seat at its end open at said cylinder, a valve plunger shiftable in said sleeve and including a valve portion at its end adapted to engage said valve seat and a reduced portion normally positioned within said sleeve, said sleeve having ports in communication with said fuel passage and open respectively at said valve seat and at the interior of said sleeve spaced from the valve portion of said plunger for communication with said auxiliary chamber, said sleeve also having a port registering with said air passage and positioned opposite the reduced portion of said plunger in all positions of the plunger, and a valve closing said last named port.

9. The construction defined in claim 8 wherein in said plunger includes a portion spaced outwardly from said last named valve to define the outer end of said auxiliary chamber, and an annular seal encircling said last named portion.

10. The construction defined in claim 8, and an insert fitting in and having a passage forming a part of said air passage, said insert projecting into said sleeve, said insert mounting said last named valve whereby said valve and insert form a preassembled unit.
